UNITED STATES PATENT OFFICE

2,476,709

ANNUAL TROUGH OIL BURNER

Nicholas W. Dockery, Rockingham, N. C., assignor
to Dockery Laboratories Co., Rockingham, N. C.

Application September 7, 1946, Serial No. 695,405

3 Claims. (Cl. 158—91)

1

This invention relates to a novel heater of the type especially adapted for use in heating a tobacco curing barn, said heater including a casing affording a combustion chamber and having at least one side outlet nipple for the exit of products of combustion and a bottom air inlet opening, and a multiple oil burner mounted in said opening, the outlet nipple being adapted for connection with a heating pipe trained about the interior of the barn and extended to a stack so that the hot products of combustion flowing through the heating pipe cause heating of the barn.

An object of the invention is to provide a simple and efficient heater of the above kind in which novel provision is made to mount the burner within the bottom air inlet opening of the casing.

A further object is to provide, in a heater of the above kind, a simple, efficient and economical oil burner which can be easily and quickly installed in the casing.

Another object is to provide an efficient multiple oil burner of the above kind including a plurality of spaced concentric annular burner sections, each section embodying an annular oil trough and an oil vaporizing ring disposed within said trough, the edges of the troughs being rounded so that the air passing upwardly about the outer section, between the adjacent sections and within the inner section will curl around said edges to effectively mix with the films of oil issuing from the burner sections between the troughs and vaporizing rings thereof and thereby insure substantially complete combustion.

Other objects and features of the invention will become apparent from the following description when considered in connection with the accompanying drawings, in which:

Figure 1 is a central vertical sectional view of a heater constructed in accordance with the present invention, partly broken away.

Figure 2 is a horizontal section taken on line 2—2 of Figure 1.

Figure 3 is an enlarged fragmentary section through the burner, taken on line 3—3 of Figure 2, and

Figure 4 is an edge elevational view of the burner.

Referring in detail to the drawings, 5 indicates a rectangular casing which affords a combustion chamber 6 and which has at least one side outlet nipple 7 for the exit of products of combustion. Formed in the bottom wall of casing 5 is a rela-

tively large central air inlet opening 8, and the casing 5 has a removable cover or lid 9.

A multiple oil burner 10 is mounted within the opening 8. In practice, the side outlet nipple or nipples 7 is or are connected with a heating pipe or pipes trained about the interior of a tobacco curing barn and extended to a stack so that the hot products of combustion flowing through the heating pipe or pipes cause heating of the barn.

10 The burner 10 includes a plurality of spaced concentric annular burner sections a, b and c, and each section embodies an annular oil trough 11 and an oil vaporizing ring 12 disposed within said trough. The troughs 11 of the burner sections 15 are joined integrally by webs 13, and are spaced apart as at 14 to provide a free air supply between the burner sections. Air is also supplied through the central opening 15 of the inner burner section and between the wall of opening 8 and the outer burner section, said opening 8 being of slightly greater diameter than the burner 10. A bored oil passage 16 which extends through the webs 13, affords communication between the bottoms of the several troughs 11, and oil is supplied to the troughs of the several burners through this passage and from an oil supply pipe 17 connected to the passage 16 at the outside of the outer burner section. Integrally formed on and at the top of the outer wall of 20 the trough 11 of the outer burner section, are horizontal projecting lugs 18 having vertical screws 19 adjustably threaded therethrough. The screws 19 rest upon the bottom of the casing 5 in surrounding relation to the opening 8 so as to support the burner within said opening in spaced concentric relation to the wall of the latter. By vertically adjusting the screws 19, the burner may be levelled and supported at the desired height with respect to the bottom wall 25 of casing 5. The vaporizing rings 12 are of slightly less depth and width than the troughs 11 and are centered within the latter by means of supporting lugs or ribs 20 integrally formed at circumferentially spaced points on the outer sides of the vaporizing rings 12. Thus, a narrow space is left between each side of each vaporizing ring and the adjacent side of the associated trough 11 so that the oil supplied to the troughs 30 will issue therefrom through the spaces 21 in thin arcuate films. The upper edges of the troughs 11 are rounded as at 22 so that the air passing upwardly about the outer burner section, between adjacent burner sections, and within the inner burner section will curl around said edges to effectively mix with the films of oil 35

issuing from the burner sections, and thereby insure complete combustion. The upper faces of the vaporizing rings are preferably slightly concave as at 23 to form shallow wells for reception of any excess oil that may be supplied to the troughs and which may be ignited in said wells by the flames at opposite sides thereof and above the spaces 21. In practice, the vaporizing rings will assume a position slightly below the upper edges of the troughs to insure passage of the excess oil into the wells 23. The troughs 11 are preferably of V-shape in cross-section, and the rings 12 are of substantially triangular shape in cross-section, as shown. This causes the films of oil to issue from the spaces 21 in upwardly diverging relation so that the flames from the several burners will intersect and cause a swirling action calculated to promote complete combustion. To aid in turning or handling the vaporizing rings 12, each is preferably provided with an upwardly projecting lug 24.

From the foregoing description, it is believed that the construction, operation and advantages of the present invention will be readily understood and appreciated by those skilled in the art. Minor changes in details of construction are contemplated, such as fall within the scope of the invention as claimed.

What I claim is:

1. In a heater, a multiple oil burner comprising a plurality of spaced concentric burner sections of continuous form, each section embodying a continuous oil trough of substantially V-shape in cross-section and an oil vaporizing ring of substantially triangular shape in cross-section disposed within said trough, spacing lugs on corresponding sides of the vaporizing rings for positioning the latter in slightly spaced relation

5 to opposite sides of the troughs, aligned webs integrally connecting the several troughs, there being a horizontal passage extending through the lower portions of the aligned webs and intersecting the several troughs at the bottoms thereof, the outer end of said passage opening through the outer wall of the trough of the outer burner section for connection with an oil supply pipe, and supporting elements for the burner carried 10 by the trough of the outer burner section.

2. The construction defined in claim 1, wherein the tops of the vaporizing rings are located slightly below the upper edges of the troughs, said vaporizing rings having concave upper faces to 15 provide shallow excess oil receiving wells.

3. The construction defined in claim 1, wherein the troughs are provided with rounded upper edges so that air passing upwardly between them will curl around said edges for effectively mixing 20 with oil films issuing from the burner sections between the troughs and vaporizing rings thereof.
